UNITED STATES PATENT OFFICE.

OLAF JOHAN STOUD PLATOU, OF CHRISTIANIA, NORWAY, ASSIGNOR TO NORSK HYDRO-ELEKTRISK KVAELSTOFAKTIESELSKAB, OF CHRISTIANIA, NORWAY.

ELECTRIC-ARC FURNACE.

1,241,655.

Specification of Letters Patent.

Patented Oct. 2, 1917.

Application filed June 2, 1916. Serial No. 101,425.

To all whom it may concern:

Be it known that I, OLAF JOHAN STOUD PLATOU, a subject of the King of Norway, residing at Christiania, Norway, have invented certain new and useful Improvements in Electric-Arc Furnaces; and I do hereby declare the following to be a full, clear, and exact description of the invention, such as will enable others skilled in the art 10 to which it appertains to make and use the same, reference being had to the accompanying drawings, and to letters or figures of reference marked thereon, which form a part of this specification.

15 In electric arc furnaces the reaction chamber is generally built of fire-brick masonry and surrounded by a shell of iron or other metal in order to prevent gas leakages through the porous furnace material. It has 20 already been proposed to place this metal shell at some distance from the wall of the reaction chamber and to use the space between as conduit for the gas supply of the furnace. According to the present invention 25 the metal shell is constituted by the magnetic material of the furnace in such a manner, that the part of the magnet construction uniting the magnet poles of each side of the furnace is given the shape of a 30 bell or hemisphere.

The annexed drawing illustrates the invention, as used in connection with a furnace of the Birkeland-Eyde type.

The drawing embodies a section through 35 the spherical or bell-shaped magnet arrangement *a*, *a*, which may be cast in one piece of iron or steel or built up of separate parts in any suitable manner, and eventually some of the parts may be of non-magnetic 40 material. The shell construction bears magnet poles *b*, the number, shape and position of which are not essential for the invention. To render the drawing fully explanatory 45 also the furnace chamber *c* with the surrounding brickwork *d* is shown. As to the magnet coils *e* the arrangement, already known heretofore, is shown, in which the air, by outside pressure or by suction from the furnace chamber, is supplied to the latter through the apertures *f* and is caused 50 to pass the magnet coils for cooling the same before entering the reaction chamber through the perforated brickwork. The electrodes in this type of furnace are generally mounted in a plane perpendicular to

the axis of the magnets. One of such electrodes is shown at *i* projecting from its insulating piece *k*.

As above mentioned the magnet construction may be built up of sections in any suitable manner, being for instance subdivided along the center line *g*, *g*. It is however very advantageous to arrange the divisions in such a manner that the brickwork may easily be laid open for inspection. This very important advantage, which the constructions hitherto used are lacking, may for instance be realized by making the magnet poles with their flanges *2*, that form part of the casing detachable at *h*. As a matter of course the 70 furnace shell must be provided with necessary apertures for the gas currents, electrodes, etc.

For the purpose of regulating the distance of the poles, the latter should be displaceable longitudinally. This may be effected either by interposing suitable adjusted metal pieces at *h* or in the manner that the pole *b* is made lengthwise adjustable in the shell *a*, as is by way of example pointed out on the 80 right hand of the drawing. For variation of the spreading effect on the flame the intensity of the magnetic field may also be varied in the manner that an inner part *b* and an outer part *b'* of the pole core are made 85 displaceable to one another, an arrangement that is likewise indicated on the right side of the figure. As illustrated the inner part *b* is adjustable relatively to the outer part *b'*.

As compared with constructions hitherto 90 known, where the magnet body and the air shell of the furnace are independent of one another, the above described arrangement offers very important advantages.

So the whole building up of the furnace is 95 considerably simplified, as the magnet construction substitutes the metal covering otherwise required. The sides of the furnace (magnet bells *a*, *a*) which already with regard to the magnetic conductivity must 100 be of considerable thickness are utilized for enhancing the mechanical stability of the furnace. In this way the disagreeable noise that is so characteristic of the furnaces, hitherto used is to a great extent eliminated. 105 The usual covering, of light plates, forms a sort of membrane which propagates and intensifies the roaring of the flames. The convex shape of the furnace shell in its new form adapts the furnace immediately for the 110

use of high gas pressures. At the same time the air space of the shell is enlarged to such an extent that a very favorable buffer effect is obtained, which is likewise conducive to quiet burning of the flame and regular working of the furnace. Finally it is obvious that also the present construction utilizes the already known effect of gas currents in the space between the reaction chamber and the metal covering, as to prevention of punctures between these parts of the furnace.

It is to be understood that the particulars of building up the magnet body and the poles are a matter of calculation and construction respectively with due reference to the special conditions of the furnace in question. The shell construction above described is by no means bound to the manner of gas conduction indicated by the drawing. In fact it is applicable to normal Birkeland-Eyde furnaces of any modification being especially useful for large furnaces.

I claim—

- 25 1. In an electric arc furnace having a magnetically spread flame; a reaction chamber surrounded by a metal shell, said shell constituting part of the magnetic construction uniting the magnetic poles.
- 20 2. In an electric arc furnace having a magnetically spread flame; a reaction chamber surrounded by a metal shell, said shell being constituted by the magnet construction and forming a free space between the wall of the reaction chamber and said metal shell.
- 35 3. In an electric arc furnace having a magnetically spread flame; a reaction chamber surrounded by a shell, said shell being con-

stituted by the magnet construction of the furnace and having approximately spherical shape forming a free space between the outside of the reaction chamber and said shell.

4. In an electric furnace having a pair of opposed magnets and a reaction chamber between them, the novelty which comprises extending the metallic magnet cores in the form of a casing for said chamber, thereby utilizing said extended metallic portion both as a casing for said chamber and as a metallic portion of the magnetic circuit between the opposed magnets.

5. In an electric furnace having a pair of magnets in operative relation to a furnace chamber between them, a metallic casing for said chamber forming air spaces between the casing and chamber, said casing having suitable openings therein for said magnets, closing plates for said openings, each closing plate forming a flange on the metallic core of a magnet.

6. In an electric furnace having a pair of magnets in operative relation to a furnace chamber between them, a metallic casing for said chamber forming air spaces between said casing and chamber, said casing being in two dome-shaped portions, each portion having an opening therein for a magnet, and a closure for each opening constituted by a flange on the magnet core.

In testimony that I claim the foregoing as my invention, I have signed my name in presence of two subscribing witnesses.

OLAF JOHAN STOUD PLATOU.
